US00D542796S

(12) **United States Design Patent** (10) **Patent No.:** **US D542,796 S**
Chan (45) **Date of Patent:** **** May 15, 2007**

(54) **CODE READER**

(75) Inventor: **Raymond Chan**, Hong Kong SAR (CN)

(73) Assignee: **IDT Electronic Products Limited**, Kowloon (HK)

(**) Term: **14 Years**

(21) Appl. No.: **29/235,682**

(22) Filed: **Aug. 4, 2005**

(30) **Foreign Application Priority Data**

Jun. 21, 2005 (HK) 0501479

(51) **LOC (8) Cl.** **14-02**

(52) **U.S. Cl.** **D14/431**

(58) **Field of Classification Search** 235/462.49, 235/462.45, 462.43, 472.01, 472.03, 494, 235/495, 482, 454; D14/431, 426, 420; D26/37; 250/555, 566, 569; 401/195; 362/118, 259

See application file for complete search history.

(57) **CLAIM**

The ornamental design for a code reader, as shown and described.

DESCRIPTION

FIG. 1 is a front perspective view of a code reader showing my new design;

FIG. 2 is a rear perspective view thereof;

FIG. 3 is a front elevational view thereof;

FIG. 4 is a rear elevational view thereof;

FIG. 5 is an elevational view showing one side thereof;

FIG. 6 is an elevational view showing opposite side thereof;

FIG. 7 is a top end view thereof; and,

FIG. 8 is a bottom end view thereof.

1 Claim, 6 Drawing Sheets

FIG. 1

FIG. 2

FIG. 3

FIG. 4

FIG. 5

FIG. 6

FIG. 7

FIG. 8
